UNITED STATES PATENT OFFICE.

ACTAEON L. DYKE, OF AKRON, OHIO.

DESIGN FOR A SHIPPING AND EXHIBITING CASE.

SPECIFICATION forming part of Design No. 20,104, dated August 12, 1890.

Application filed July 14, 1890. Serial No. 358,747. Term of patent 7 years.

To all whom it may concern:

Be it known that I, ACTAEON L. DYKE, a citizen of the United States, and residing at Akron, in the county of Summit and State of Ohio, have invented and produced a new and original Design for a Case for Shipping and Exhibiting Marbles, reference being had to the accompanying drawing, forming a part thereof.

10 The drawing is a plan of the case.

The design consists in a case divided into several compartments, one of the compartments A being centrally located and surrounded by the other compartments B. Compartment A represents a circular or elliptical figure inscribed within a square or rectangular figure. The compartments B are rectangular or square, and are arranged around the central compartment A.

What I claim is—

20 The design for a case for shipping and exhibiting marbles herein shown and described, the same comprising several compartments, one of the compartments being centrally located and representing in plan a circular or 25 elliptical figure inscribed within a square or rectangular figure and being surrounded by the other compartments.

In testimony whereof I sign this specification, in the presence of two witnesses, this 30 day of June, 1890.

ACTAEON L. DYKE.
